UNITED STATES PATENT OFFICE.

NOAH S. HARTER, OF WAUKEGAN, ILLINOIS, ASSIGNOR OF ONE-THIRD TO GEORGE F. RUMMEL AND ONE-THIRD TO A. T. WEAVER, BOTH OF CHICAGO, ILLINOIS.

GAME APPARATUS.

Application filed May 18, 1921: Serial No. 470,569.

To all whom it may concern:

Be it known that I, NOAH S. HARTER, a citizen of the United States, residing at Waukegan, in the county of Lake and State 5 of Illinois, have invented certain new and useful Improvements in Game Apparatus, of which the following is a specification.

The invention relates to game apparatus.

One of the objects of the invention is to 10 improve games.

Another object is to provide improved apparatus by means of which one may practice to improve his skill in playing golf.

Another object is the provision of means 15 which may be used indoors or out of doors in a relatively small area, by the use of which the stance of the player, the swing of his club, the accuracy of the stroke and impact of the ball, as in golf, may be acquired by practice.

Another object is to specifically improve the apparatus used in carrying the invention into effect.

Other, further and more specific objects 25 of the invention will become readily apparent, to persons skilled in the art, from a consideration of the following description when taken in conjunction with the drawings, wherein:-

30 Fig. 1 is a front elevation of the simplest form of target showing the stroke indicating device connected thereto.

Fig. 2 is a plan view of the same.

35 Fig. 3 is a section taken on line 3—3 of Fig. 1.

Fig. 4 is an end view of the device as shown in Fig. 2.

Fig. 5 is a modification of Fig. 1.

Fig. 6 is another modification of Fig. 1.

40 Fig. 7 is an elevation of the more elaborate form of target.

Fig. 8 is a plan view of Fig. 7.

Fig. 9 is a modification of Fig. 7 similar to Fig. 6.

45 Fig. 10 is a plan of the same.

Fig. 11 is an enlarged detail of the lacing means.

Fig. 12 is a section thru line 12—12 of Fig. 11.

50 In all the views the same reference characters are employed to indicate similar parts.

The generic idea involved in the invention is the provision of a vertically upstanding target composed of fabric or netting,

properly arranged and supported so that a given impact of the ball with any portion thereof transmits an impulse thru suitable cords to an impulse recorder, thereby registering in terms of yards the force of the 60 stroke applied to the ball and the effect thereof when it impinges upon the face of the target.

Another feature of the invention, included in all of the modifications, is the 65 means for protection of the relatively unyielding portions of the target support, by use of suitable fabric sheets, so as to cushion the ball and prevent its rebound to the injury of the player when it strikes unyielding objects.

The device except Fig. 1 is shown to be contained within a room or other suitable enclosure the walls of which are designated by 13 in the several figures.

In the simplest form of the structure, shown in Figs. 1 and 2, the target 15 is made of suitable fabric or netting, suspended between a rectangular frame consisting of the members 16, 17, 18 and 19. Each of the targets is laced to the side frame members, as shown in Figs. 7 to 12, inclusive, the laced cord engaging the vertical edges of the target and passing over pulleys or sheaves. Each of the sheaves 20 is provided with an 85 attaching portion 21 and a ball bearing roller 22, partly covered by a casing 23. The cord 24, which should be flexible and unyielding as can be, passes alternately thru a sheave secured to the edges of the 90 target 15 and to a sheave supported, as by a hook 25, on the side members 16 and 17. For the purpose of strength it is desirable to stitch a cord 26 along the edges of the 95 target and to extend it into loops 27^a for engagement with the part 21 of the sheave 20. In Fig. 7 the cord 24 is tensioned by the weight 27. The cords from each side pass thru a ball bearing sheave 28 at which point they are connected together to tension the 100 cords on both sides of the structure. Each of the cords are then threaded thru the sheave 20 and in order to equalize the effect of the blow by the flying ball upon the target, when the target is of extreme length, the cords are extended back of the target over a ball bearing sheave 29 and connected to the impulse indicator 30. In the case referred to another weight 27' is located near the bottom of the target, the cords 24 being 110

connected thereto and passing over the pulley 28' from which they are laced on the respective sides of the target thru the sheaves 20, and it is carried parallel with the cord 5 from the upper section of the target over the pulley 29 and there it is connected with the cord extending to the impulse indicator.

Now, it will be manifest, that when a ball strikes the target 15, as shown in Fig. 7 and 10 specifically described, that an impulse will be imparted to the target 15 by the effect of the motion of the ball which will cause the cord 24 to pull on a portion of the target indicator and rotate the index over the dial.

15 A target recorder well adapted for this use is more specifically shown and claimed in my co-pending application Serial Number 470,570, filed May 18, 1920, and does not need any further explanation.

20 In Figs. 6, 9 and 10 the target is divided in two angularly related sections 15 and 15' laced to a frame having side members 16 and 17 in the rear of the target, but laced in the manner, as more clearly shown in 25 Fig. 9 and as heretofore described.

The cords for the target 15 pass thru slots 31 made near the inner edge of the target section 15. The tension weights 27 and 27' maintain the target, and the cords by which 30 it is supported, taut so as to be extremely sensitive to the effect of the blow or pressure that may be imparted thereto by the ball.

In Figs. 1, 2 and 8 there is placed before the wood work of the structure cushioning 35 curtains 32 and 33. These curtains or cushions extend to and overlie the vertical edges of the target 15, so that when the ball misses the target it hits one of these curtains and prevents violent rebound of the ball. In 40 Figs. 6 and 10 they are not required because the wood work is behind the target.

In Fig. 5 I have shown fabric or net cushioning curtains 33 and 34 properly supported and stretched, from the ceiling to the 45 floor substantially shown in Fig. 3, and other cushioning curtains 35 and 36 extending from the outer edges of the curtains 33 and 34, respectively, closely to the walls of the side of the room so that when the ball is 50 driven towards the target 15, if it does not strike the target it will strike one of the cushioning curtains and will not rebound with the vigor that it would if it struck some substantially unyielding object such as the 55 frame upon which the target is stretched. By this means the frame and all wood work adjacent the target are protected against contact by the ball for the reason heretofore described.

60 In Fig. 6 the cushioning curtains 37 and 38 are substantially parallel with the side walls of the room as shown in Fig. 3. The

lower edges of the curtains are secured to the floor, as at 39, by suitable means, and laced or otherwise fastened to the ceiling 65 and supported, so that the cushioning curtains are held taut to absorb the shock that may be imparted to them by the flight of the ball.

When any one of the targets is struck by 70 the ball tension is applied to the cords 24 leading to the target, and the pointer 41 of the indicator is moved over the dial, shown in Fig. 7, to be marked or scaled from zero to 275 yards. The arrangement of the stroke indicator is such that the index or pointer 75 41 will remain in the position in which it has been placed by the force of the impact of the ball against the target, until it is manually returned to the zero point, as more 80 clearly shown in my copending application.

The indicator is actuated by a spring which responds to the impulse to move the index before the inertia of the tensioning weights 27-27' can be overcome to move 85 them by force of the same impulse.

Having described my invention what I claim as new and desire to secure by Letters Patent, is:—

1. A device of the character described 90 comprising a frame; an impact indicator; an inertia weight and a fabric target tensioned by the inertia weight and the indicator and supported on the frame.

2. A device of the character described 95 comprising a frame; an impact indicator; an inertia weight; a fabric target having one edge connected to the indicator and another edge to the inertia weight and supported by the frame.

3. A device of the character described comprising a fabric target; a frame to support the target; an impact indicator; a cord interlaced between the vertical edges of the target and the frame, one end of which is connected to the indicator to transmit the effect of the impact of the ball on the target to the indicator; an inertia weight connected to the other end of the cord to hold the cord taut and cushioning curtains erected before 100 the frame, one on each side of the target.

4. A device of the character described comprising a fabric target made in two sections, interlapped at their approximate vertical edges; a frame, to support the target; a cord, interlaced between the targets at their adjacent edges and adjacent members of the frame, respectively, and an impact indicator to which said cord is connected to indicate an impulse produced by impact of 115 the ball upon either target.

In testimony whereof I hereunto subscribe my name.

NOAH S. HARTER.
